UNITED STATES PATENT OFFICE.

ERNEST P. MULLER, OF NEW YORK, N. Y., ASSIGNOR OF ONE-HALF TO
J. K. YOUNG, OF SAME PLACE.

DESIGN FOR AN ADVERTISING-CABINET.

SPECIFICATION forming part of Design No. 33,484, dated October 30, 1900.

Application filed September 8, 1900. Serial No. 29,470. Term of patent 14 years.

To all whom it may concern:

Be it known that I, ERNEST P. MULLER, a citizen of the United States, residing at New York, (Brooklyn,) in the county of Kings and State of New York, have invented and produced a new and useful Design for Advertising-Cabinets, of which the following is a specification, reference being had to the accompanying drawing, in which an advertising-cabinet embodying my design is shown in perspective.

As shown in the drawing, the leading feature of my design consists of a cabinet or body 1, the lower portion 2 of which is rectangular in outline and the upper portion 3 is of the same width as the base and substantially rectangular in elevation, but semilozenge-shaped in horizontal cross-section. The depth or distance from the front to the rear of the top or upper portion is less than the depth of the base, whereby a step or offset 4 is formed on top of the base. The upper end of the top is cut off at each corner, as shown

at 5, and the center is extended upward, as at 6, to correspond with the central face. 25 Each of the faces of the top and bottom, except the back, which is plain and smooth, is divided into projecting fields or divisions 7, one of which, 8, near the top, is larger than the others and forms a mirror which is provided with a curved surface, whereby the image or reflection is distorted or made to represent the object before it in a grotesque or comic position. The divisions except the mirror are adapted to be provided with advertising matter. 35

Having described my invention, what I claim as new, and desire to secure by Letters Patent, is—

The design for an advertising-cabinet, as 40 herein shown and described.

ERNEST P. MULLER.
